RECORDER FOR FACSIMILE SYSTEMS

Filed Dec. 19, 1928

Inventor
R. H. RANGER

By his Attorney, *Dr. J. Adams*

UNITED STATES PATENT OFFICE

RICHARD HOWLAND RANGER, OF NEWARK, NEW JERSEY, ASSIGNOR TO RADIO CORPORATION OF AMERICA, A CORPORATION OF DELAWARE

RECORDER FOR FACSIMILE SYSTEMS

Original application filed August 12, 1926, Serial No. 128,720. Divided and this application filed December 19, 1928. Serial No. 327,009.

The present invention relates to a recording system and means for use in connection with facsimile apparatus and the like in which the recording action is, what has become known in the art as "pyro recording," this term being applied to a system for recording electrical impulses by translating them into heat and then applying the resulting heat pulses to a heat sensitive paper.

10 The present application forms a divisional part of my copending application, Serial No. 128,720, filed on August 12, 1926.

Similar to the parent application, the system herein disclosed has particular reference to recording by means of a heated jet of air, gas, or fluid projected upon a chemically treated heat sensitive paper of the character, for example, disclosed by my copending application which was filed jointly with 15 Richard Stuart Bicknell, Serial No. 303,108 on August 31, 1928, or, for example, a paper of the character disclosed in my co-pending application filed jointly with Francis G. Morehouse on December 7, 1928, as Serial 20 No. 324,421, or, if desired, the system may be used in connection with any other appropriate form and type of recording mediums 25 which will respond to an application of heat to produce a pictorial or even non-pictorial 30 record.

While the application here, as in the parent case, is directed particularly to the recording of pictures, it is to be understood, that I intend to use the word "pictures" in a 35 generic sense and include thereby all printed matter which is capable of being viewed by the optic senses and may include therein, pictures, newspaper articles, checks, documents, affidavits, finger prints, fashion plates, 40 magazine covers, views, blueprints, financial statements, and, in fact, all types of printed matter.

An object of this invention is, therefore, to 45 provide a system and means for supplying or projecting heat to or against a heat sensitive recording surface and, at the same time, to provide a novel and efficient means for controlling the amount of heat which is directed 50 against the recording surface.

Other objects of this invention will at once suggest themselves by a reading of the specification and claims in connection with the accompanying drawings although, it is to be understood, that it is, of course, among the 55 objects of this invention to provide a system whereby recording action may be produced easily by the aid of a recording means of the character described in which there is high efficiency, durability, convenient operation, 60 compactness, substantial fool-proof operation, and minimum installation expense.

The single figure of the drawing illustrates a schematic embodiment which my invention may assume although, it is to be understood, 65 that various modifications and changes may be made in the apparatus disclosed in so far as these changes fall fairly within the spirit and scope of the invention as defined by the hereinafter appended claims.

Now, to refer specially to the accompanying drawing, air, or other appropriate gas or fluid, may be supplied from an external source (not shown) to an inlet tube 1 of a nozzle system, generally designated "A". The nozzle 70 "A" is provided at one end thereof opposite the air, gas or other fluid in-take with a jet portion 3 which directs the medium contained within the nozzle against the recording surface 5, which is preferably in the form of a pyro recording paper of the character named by my above identified copending applications. The air, gas or fluid contained within the nozzle system "A" supplied from the source is under a predetermined and regulated pressure and, therefore, the jet portion 75 3, being of very small diameter tends to project the medium at a relatively high velocity against the recording surface 5.

The recording surface 5 which is to be subjected to the action of the jet of air, gas, or other appropriate fluid from the nozzle 3 is carried and supported by the supporting surface 7, which is preferably in the form of a drum and which may rotate continuously 85 with respect to the jet 3 and advance relatively thereto in a spiral path, or which may be so associated with the jet that the jet is arranged to trace a path longitudinally of the supporting drum and at the end of each lon- 90 95 100

5 gitudinal stroke of the jet with respect thereto the drum 7 will be rotated or advanced in the direction of the arrow an amount equal to one line advance of the picture. The line advance may be of any desired and chosen amount, depending upon the amount of detail desired. As a suitable amount of advance 1/80 of an inch on the circumference has been found to be quite suitable

10 10 for providing sufficient detail for all practical purposes, although other line advances may be used where desired.

Surrounding the jet "A" at a point near the take-in tube 1 I have provided two clamping rings 9 and 11 to which conductors 13 and 15 respectively are connected. Energy is supplied to the conductors from an external source (not shown) which may, if desired, be a battery. By connecting heated coils 14, 20 of the general character shown and described in connection with Figs. 1 and 2 of the parent application, of which this forms a divisional part, with conductors 13 and 15, the air, fluid, or gas, flowing through the nozzle system may 25 be appropriately heated to the desired temperature for recording. As in the parent case, the heating coils 14 may consist of the usual wrapping of a fine conductor about the tube carrying the recording medium within 30 the nozzle and so arranged as to heat the medium as it flows therethrough.

In order to confine as much heat as possible within the nozzle "A" and thus heat the recording medium to a higher degree of temperature I have provided an asbestos coating 35 17 about the nozzle "A" and may secure this coating thereto by an appropriate method, for instance, by clamping rings or wires 19.

The entire nozzle portion "A" is preferably 40 supported by means of a slideable frame work 21 upon a plate member 23 carried by a U-shaped supporting member 25. The entire nozzle may be adjusted vertical with respect to its support bracket by turning the thumb 45 screw 26 and adjusted horizontally with respect to the same support and the recording surface 5 by means of the thumb screws 27 and 29, which are so arranged that upon being loosened they may provide through a slot 50 portion 28 a slideable movement for the nozzle.

Carried by the U-shaped supporting bracket 25 I have provided a telephone receiver 31 which is supplied with energy through conductors 33 and 35. These conductors 33 and 55 35 are in turn connected with a receiving system of any desired type, for instance, of the type claimed and described in my copending applications Serial No. 615,175, filed February 16, 1924, and Serial No. 759,514, filed November 18, 1924. If desired, any other appropriate type of receiving systems may be used and so arranged as to have the output energy therefrom supplied to the conductors associated with the receiver 31.

65 A thin rod 37 is attached to the diaphragm

39 of the telephone receiver at a point 41, for example, and vibrations in the receiver produced in accordance with variations in the strength of signals supplied thereto from the receiving system will cause the rod 37 to move up and down a proportionate amount in a well known manner. The rod 37 at its upper end 43 is pivotally connected with a pivot rod 45 pivoted at a point 47 closely adjacent to the point of connection 43 with the rod 37, so that the end of the rod 45 remote from the rod 37 will have translated thereto a proportionately large displacement due to a slight movement of the diaphragm 39.

Connected to the end 49 in a pivotal manner is a shutter 51, which is supported by the guides 53 and 55, respectively, so that upon a movement of the diaphragm 39 up and down in accordance with the received signals the shutter 51 will slide in the guides and likewise move up and down. The motion of the shutter will, by the manner of linking the actuating rods, be much greater than that of the diaphragm 39.

The shutter 51 is provided with an orifice 57 which, under normal conditions is directly in front of the opening in the jet 3 through which the air, gas or other fluid, is projected, so that this recording medium may then be directly passed therethrough toward the recording surface 5. However, when signals are received so as to move the diaphragm of the receiving telephone 31 up and down this motion is translated to the shutter system 51 and the latter will also move up and down and prevent the heated recording medium from striking the recording surface 5 and thus will permit the making of marks on the recording surface which corresponds to, or closely approximate, a transmitted picture or the like.

In order to prevent the recording medium, projected from the jet 3 through the orifice 57 in the shutter 51, from spreading over a large area of the recording surface I have provided a means to confine the heat from the jet to a small differential section of the recording medium, which may, for example, be an L-shaped standard 59 positioned between the recording surface 5 and the shutter 51. This L-shaped standard 59 is supported rigidly with respect to the support 23 for the nozzle system "A" in any desired manner. In this standard 59 I have provided an orifice 61 which will serve as a diaphragm and determine the area over which the recording medium from the jet 3 may be distributed. If desired, this opening or orifice 61 may be formed so as to be adjustable as regards its size, although for convenience of illustration this arrangement has not herein been illustrated.

While the system has herein been illustrated and described as consisting of a shutter mechanism which moves up and down with

respect to the jet 3 associated with the nozzle system "A", it is also within the contemplation of this invention to provide a shutter control system in which the shutter is not regulated as to its up and down movement with respect to the jet. Such a system may be provided by pivotally mounting the shutter at a fixed height with respect to the jet and arranging the same so as to tilt or oscillate with respect to the jet 3, and thus control the flow of the recording medium from the jet in any desired or appropriate manner. This may be accomplished, for example, by providing a system of bell-crank levers operable from the diaphragm member 39, and still fall within the spirit and scope of this invention.

Having now described my invention, what I claim and desire to secure by Letters Patent is:

1. An arrangement for recording pictures comprising a rotatable drum support for carrying a heat sensitive recording medium, means for projecting a heated recording fluid upon said support for producing a record thereon, means for controlling the amount of said heated recording fluid directed to said recording surface, said control means including a shutter and a diaphragm associated therewith whereby the said shutter is moved toward and away from the point of projecting said recording medium in proportion to the strength of signal impulses reaching and influencing said diaphragm.

2. An arrangement for recording pictures comprising a rotatable drum support for carrying a recording sheet having a heat reduceable metallic compound coating thereon, means for directing a hot air blast against said sheet for producing a chemical change to the body thereof, and means for controlling the amount of heat from said air blast which reaches said sheet, said control means including a shutter and a telephone diaphragm connected thereto, whereby said shutter is moved toward and away from said blast proportional to the strength of signalling impulses reaching said diaphragm.

3. An arrangement for recording pictures and the like including a fluid recording means, a support adjacent thereto for carrying a heat sensitive surface, means for heating the fluid within said recorder, means for projecting the said heated fluid against said support, and a shutter means operable in accordance with the strength of received signals for controlling the amount of said heated fluid directed against said support surface.

4. In a recording system for pictures and the like, a nozzle system, a support for carrying a heat sensitive recording surface, means for moving the nozzle and said support relatively to each other, means for introducing into said nozzle system a recording medium, means for heating said recording medium within said nozzle, means for projecting said

heated recording medium from said nozzle toward said support, and a shutter means operable in accordance with received signals for controlling the amount of said recording medium projected from said nozzle to said support surface.

5. In a facsimile recording system, a nozzle system, means for supplying a recording fluid thereto, means for heating said recording fluid within said nozzle, means for projecting the said heated recording fluid from said nozzle, a support surface adjacent said nozzle for supporting a heat sensitive recording medium, and a shutter means having an opening therein positioned between said nozzle and said support for controlling the amount of heated recording medium directed from said nozzle to said support in accordance with received signalling impulses.

6. In a recording system for pictures and the like, a nozzle system, means for supplying a recording fluid thereto, means for heating said recording fluid, means for projecting said heated recording fluid from said nozzle system, a support surface for carrying a heat sensitive recording surface adjacent to said nozzle, means for obtaining a relative movement between said nozzle and said support surface whereby the recording action is produced over substantially the entire recording surface carried by said support, and a shutter system interposed between said nozzle and said support for controlling the amount of heated fluid projected from said nozzle to said support.

7. In a recording system for facsimiles, a support surface, means for projecting a heated gaseous blast against said support and normally with respect thereto, a shutter means interposed between said projecting means and said support surface for regulating the amount of said heated gaseous blast projected against said support surface, and a link system operable in accordance with received signal pulses for controlling said shutter means.

8. In a recording system for pictures and the like, a support surface for supporting a heat sensitive recording surface, means for projecting a heated air blast normally with respect to said support, means for moving said projecting means vertically and horizontally for adjusting the same with respect to said support, means for obtaining a relative movement between said support and said projecting means, and a shutter means interposed between said heated air projecting means and said support for controlling the amount of heated air directed against said support in accordance with the strength of received signalling impulses.

9. The system for recording pictures and the like claimed in claim 8 including, in addition, a diaphragm carried between said control means for said heated air and said support for determining the area over which

said heated air may be projected on said support surface.

10. An arrangement for recording pictures comprising a rotatable drum support for carrying a heat sensitive record surface, means for projecting a heated recording fluid upon said support for producing thereon a record of received pictures, and a shutter means for controlling the amount of said heated recording fluid reaching said recording surface.

11. An arrangement for recording pictures and the like including a heated recording system, a support adjacent thereto for carrying a heat sensitive recording surface, means for projecting the said heated fluid against said support, and a shutter means operable in accordance with the strength of received signals for controlling the amount of said heated fluid directed against said support surface.

12. In a recording system for pictures and the like, a nozzle system, a support for carrying a heat sensitive recording surface, means for moving the nozzle and said support relatively to each other, means for introducing into said nozzle system a recording medium, means for heating said recording medium, means for projecting said heated recording medium from said nozzle toward said support, and a shutter means positioned between said nozzle and said support for controlling in accordance with received signal pulses the amount of said recording medium projected from said nozzle which reaches said support surface.

13. In a recording system for pictures and the like, a support surface for carrying a heat sensitive recording medium, means for projecting a heated recording fluid normally with respect to said support surface, means for obtaining a relative movement between said support surface and said fluid projecting means, and a shutter positioned between said fluid projecting means and said support surface for controlling the amount of heated recording fluid projecting against said support surface.

14. In a recording system for facsimiles, a support surface, means for projecting a heated gaseous blast against said support and normally with respect thereto, and a shutter means interposed between said projecting means and said support surface for regulating the amount of said heated gaseous blast projected against said support surface in accordance with received signal pulses.

RICHARD HOWLAND RANGER.
